DESIGN FOR A COMBINATION BEVERAGE DISPENSER RECEPTACLE AND SUPPORT

Edward C. Scanlon, Providence, R. I., assignee to
Clifford A. McBride, East Providence, R. I., do-
ing business as General Products Company,
Providence, R. I.

Application July 24, 1939, Serial No. 86,214

Term of patent 14 years

To all whom it may concern:

Be it known that I, Edward C. Scanlon, a citizen of the United States of America, residing at Providence, in the county of Providence and State of Rhode Island, have invented a new, original, and ornamental Design for a Combination Beverage Dispenser Receptacle and Support, of which the following is a specification, reference being had to the accompanying drawing, forming part thereof.

The figure is a perspective view of a combination beverage dispenser receptacle and support, embodying my new design.

I claim:

The ornamental design for a combination beverage dispenser receptacle and support, substantially as shown.

EDWARD C. SCANLON.
